E. BEACH

FLUSH TANK APPARATUS

Filed Dec. 9, 1925

INVENTOR,
Edmund Beach,
BY *John Stewart*
ATTORNEY

Wm. Bell. FIG. 3.

UNITED STATES PATENT OFFICE.

EDMUND BEACH, OF PATERSON, NEW JERSEY.

FLUSH-TANK APPARATUS.

Application filed December 9, 1925. Serial No. 74,287.

To all whom it may concern:

Be it known that I, EDMUND BEACH, a citizen of the United States, residing at Paterson, in the county of Passaic and State 5 of New Jersey, have invented certain new and useful Improvements in Flush-Tank Apparatus, of which the following is a specification.

This invention relates to flush tanks for 10 water closets and its object is to provide a flushing apparatus whose construction shall be as simple as possible and whose operation shall also be reliable and require little attention and the use of only inexpensive parts 15 to keep it in order.

In my apparatus the water tank is movable vertically and controls the water inflow,—when depressed by the weight of the water therein, shutting off the inflow, but 20 when the water has been withdrawn and the tank is thereupon elevated by suitable means, allowing such inflow. This is not in itself new; but it is new to introduce the water through an upwardly open valve-seat adapt- 25 ed to be closed by a downwardly moved valve which is seated by the tank as it is filled, thus simplifying the mechanism and rendering the closing action certain, and this constitutes one feature of the present invention. 30 Another feature consists in placing the tank in a water-tight casing which has a discharge outlet and providing for overflow of the tank into the casing; the overflow may be by way of an outlet formed as a stand- 35 pipe which surrounds the inlet pipe (having the mentioned valve-seat), and in that case the standpipe will afford the part of the tank structure to which the means for opening and closing the valve is connected.

The discharge of the tank may be effected 40 in any way, as by providing a service outlet therein normally closed by a valve. This valve may be manually operated; or I may construct the entire apparatus so that automatic intermittent flushing may be carried 45 on by using means to evacuate the tank including a valve device, as a float valve, for this service outlet that is movable up and down in some part of the apparatus with respect to which the tank moves vertically and 50 which valve device has its own downward range of movement short of that of the tank, this constituting a third feature of the invention.

55 In the drawing,

Fig. 1 is a vertical sectional view of a

flushing apparatus embodying the invention;

Fig. 2 is a plan thereof; and

Figs. 3 and 4 are longitudinal and trans- 60 verse sectional views, respectively, of the mentioned automatic type of the apparatus.

Let *a* designate a part of fixed structure, here in the form of a casing open only at the top and provided with a removable cov- 65 er *a'*, and also water-tight. Another part of such fixed structure is a water-supply pipe *b* extending up through the bottom of the casing and suitably secured to the same and having an upwardly opening valve-seat *c*, 70 the latter being in the present example actually formed in an extension *d* of the said pipe which is bent downward to form a discharge leg and has over the valve-seat an externally threaded opening *d'* normally 75 closed by a cap *e* screwed thereon; the extension *d* may be screwed onto the pipe *b* and it may have a spider *d''* below the valve- seat.

The casing contains a water tank *f* mov- 80 able up and down therein and when empty held at a suitable elevation by any suitable means, as plate-springs *g* secured on the bottom of the casing. The tank has a standpipe *h* which loosely embraces the pipe *b* and 85 reaches suitably above that level, indicated at *x* in Fig. 1, which is the normal filling level of the tank; said standpipe affords in effect a safety outlet, i. e., it constitutes means, usual in flushing apparatus, for af- 90 fording overflow, the water which flows over the top of and down through the standpipe in the present case being received by the casing from whence it is discharged through the pipe *i* suitably secured to the bottom of 95 the casing and being in the present example the mentioned discharge outlet.

The valve for closing the valve-seat *c* is indicated at *j*. It is in the present case a simple spindle which penetrates and is guided by the cap *e* and also by the spider; its actual seating portion is preferably a rubber or leather washer *j'*. When the tank falls this valve is moved downwardly there- 100 by and closes the valve-seat and when the tank rises it releases the valve, the down- 105 ward movement in the present case being accomplished by a lever *k* which is fulcrumed on an arm *e'* of the cap and has a pivotal connection *k'* with the valve and a link *l* 110 which is pivoted to the lever and, depending therefrom, extends freely through a hole *m*'

in a projecting lug of a collar *m* secured to the standpipe, the lower end of the link being bent off.

A short length of pipe at *n* suitably secured in the bottom of the tank *f* and preferably projecting into the pipe *i* forms the service outlet of the tank. *o* is a float valve for closing the service outlet, the same being of well known type and including an upwardly projecting stem *o'* connected with a lifting link *p* which is in turn connected with a manually operated lever *q* fulcrumed in a part of the fixed structure, as casing *a*, the connection between *o'* and *p* being such that when the valve has been lifted by *p* clear of its seat it may be by floatation moved upwardly independently of *p*, returning to its seat on the evacuation of the tank.

In Figs. 3 and 4 the automatic intermittent operation is due to the following construction: The float valve *q* controlling the service outlet has its stem *q'* slidable vertically in an arm *r* secured to a part of the fixed structure, as casing *a*; and the bent-off end *q''* of said stem is adapted to limit the downward movement of the valve short of that of the tank when, in being filled, it descends.

In Figs. 1 and 2 the operation is as follows: When the means *o p q* is operated to lift the valve *o* from its seat the tank will be evacuated and the load of the water being removed it will rise, permitting the pressure of the water in pipe *b* to lift valve *j* and the water to flow into the tank. The means *o p q* being released so that *o* returns to its seat, the tank again fills and under the weight of the water descends and so closes valve *j*.

In Figs. 3 and 4, when the tank in being filled and consequently descending reaches a certain level the downward movement of the valve *q* therewith is checked by its bent-off end *q''*, which opens the valve and initiates the evacuation of the tank, the valve remaining floating and open until evacuation is complete. In the consequent rise of the tank valve *j*, which was previously closed by the downward pressure of the tank, now opens and allows the water to flow in and, upon valve *q* assuming its seat, to refill the tank, resulting in the tank again descending to bring about a repetition of the operation.

Having thus fully described my invention what I claim and desire to secure by Letters Patent is:

1. In combination fixed structure including an upstanding water-supply pipe, a tank movable up and down and having a service outlet, means to control the flow of water from the outlet, downwardly yielding means arranged on said structure and carry-

ing the tank and normally urging the same upwardly and adapted to yield downwardly on admission of water to the tank, said pipe being arranged to discharge into the tank and having an upwardly opening valve seat, a valve movable down against the seat, a lever fulcrumed on said pipe and connected with the valve and movable downwardly to seat the same, and means, connecting the tank and lever, to transmit downward movement of the tank to the lever.

2. In combination, fixed structure including a water-supply pipe having an upwardly extending portion, a tank movable up and down and having a service outlet and also having a standpipe rising from its bottom and affording an overflow outlet from the tank and having said portion of the pipe extending loosely up through the standpipe, means to control the flow of water from the service outlet, downwardly yielding means arranged on said structure and carrying the tank and normally urging the same upwardly and adapted to yield downwardly on admission of water to the tank, said pipe being arranged to discharge into the tank and having an upwardly opening discharge seat, and means connected with the standpipe to cut off the flow through the water-supply pipe when the tank moves downwardly.

3. In combination, fixed structure including a water-supply pipe and a water-tight casing, a tank movable up and down in the casing and having a service outlet, means to control the flow of water from said outlet, downwardly yielding means arranged in the casing and carrying the tank and normally urging the same upwardly and adapted to yield downwardly on admission of water to the tank, said pipe being arranged to discharge into the tank, and means connected with the tank to cut off flow through said pipe when the tank moves downwardly, the casing having means into which said outlet discharges to carry off water delivered from the tank.

4. In combination, fixed structure including a water-supply pipe, a tank movable downwardly to a predetermined level and also upwardly and having a service outlet in its bottom, downwardly yielding means arranged on said structure and carrying the tank and normally urging the same upwardly and adapted to yield downwardly on admission of water to the tank, said pipe discharging into the tank and a valve guided by said structure and movable up and down with the tank and arranged to close said outlet and having its downward movement limited by said structure short of the downward movement of the tank.

In testimony whereof I affix my signature.
EDMUND BEACH.
